UNITED STATES PATENT OFFICE.

EDWARD F. WELCH, OF LAWRENCE, MASSACHUSETTS.

CENTRIFUGAL PUMP.

No. 889,164.

Specification of Letters Patent. Patented May 26, 1908.

Application filed August 9, 1907. Serial No. 387,756.

To all whom it may concern:

Be it known that I, EDWARD F. WELCH, of Lawrence, county of Essex, State of Massachusetts, have invented an Improvement in 5 Centrifugal Pumps, of which the following description, in connection with the accompanying drawings, is a specification, like characters on the drawings representing like parts.

This invention relates to that class of centrifugal pumps in which a series of rotary blades or impellers are provided within a casing, and the water is forced outwardly as they are rapidly rotated.

In the ordinary action of a centrifugal 15 pump, if the blades of the impeller extend exactly radially, the force which acts to pump the water will be centrifugal, but, if the blades are extended rearwardly with relation to the direction of rotation, this action 20 becomes partly positive, that is, a sort of wedging action begins to take place, which action increases as the blades approach the tangent. The more nearly the blades approach the tangent the greater is the extent 25 which they are enabled to act in this manner, and therefore, other things being equal, the greater the force with which the water may be ejected. In pumps of this character the pumping action is often much impeded by 30 the action of the water in falling back between the blades, and in being carried around between them practically "dead".

In order to increase the pressure with 35 which the water is ejected, it is customary to arrange two or more pumps in tandem. This increased attendant expense is, of course, objectionable, but the lack of efficiency in this method is its chief objection.

The object of my invention is to produce a 40 centrifugal pump in which the blades adjacent the periphery are so arranged as to approach the tangent as closely as practicable in order that the water may be forced from the casing at as high a pressure as possible, 45 and in which back-flow of water between the blades will be prevented and the whole volume of water will be constantly forced outwardly.

For an understanding of the means which 50 I employ in carrying out this object, reference is made to the accompanying drawing, in which,

Figure 1 is a side elevation of the outer casing of the centrifugal pump provided 55 with my invention. Fig. 2 is a similar view

on an enlarged scale with one end of the casing removed. Fig. 3 is a central vertical section on the line 3—3 of Fig. 2. Figs. 4 and 5 are face views of portions of the impeller. Figs. 6 and 7 are detail sectional views of the impellers.

The casing of the pump comprises circular end walls a , a' , and an involute side wall a^2 , the latter having tangential discharge outlet a^3 leading therefrom, and the wall a having a central inlet a^4 . The end walls a , a' are dished so that they converge as they approach the side wall a^2 , so that the inclosed cubical contents for each section of radius will be approximately the same. The walls a , a' are provided with bearings a^5 and a^6 respectively, which lead into the casing chamber and a pair of shafts b and c are respectively journaled therein in axial alinement.

An impeller hub d is rigidly mounted upon 75 the inner end of the shaft b and said hub is provided with a circular side wall d' , which extends therefrom for approximately half the diameter of the impeller. A series of blades e extend from the hub d to the edge of wall d' , and are preferably cast integral with said hub and said wall.

An annular wall d^2 is formed integral with said blades e at their opposite ends from wall d' , said wall d^2 extending radially from a point between the edge of wall d' and the hub to the waterway between the impeller and the side a^2 of the casing, said walls d' , d^2 , converging to correspond with the adjacent end walls a' , a . A series of supplementary blades f are provided midway between the blades e which extend from the inner edge of wall d^2 to the outer edge of wall d' and are formed integral at their ends with said walls d' , d^2 respectively. An impeller hub g is 95 mounted on the shaft c and is provided with an integral, circular, imperforate wall g' , which extends the same radial distance from the axes as the wall d^2 , said wall lying closely adjacent the outer side of wall d' . A series 100 of blades h are arranged with their inner edges adjacent the outer edges of blades e and f , with their ends integral with wall g' and an annular wall g^2 , which is located close to the inner side of wall d^2 and extends the 105 same radial distance as said blades h . A series of blades i are arranged with their inner edges adjacent the outer edges of blades h , and with their ends respectively integral with the wall d^2 and an annular wall d^3 , 110

which is located adjacent the inner side of wall g' . A series of blades k are arranged with their inner edges adjacent the outer edges of blades i and with their ends respectively integral with the wall g' and an annular wall g^2 which is located close to the inner side of wall d^2 , and extends to the outer edge thereof.

In operation the shafts b and c will be rotated in opposite directions, they being rotated respectively in the direction of the arrows, x and y in Fig. 2. As best shown in Fig. 2, all of the blades have convex acting-faces and all of them extend rearwardly, with relation to their direction of rotation, as they extend radially. The extent, however, which each successive set of blades approach the tangent, increases as they approach the periphery, so that the outer portions of the blades k extend nearly in a tangential direction. The outer edges of the blades of each set also extend approximately opposite their inner edges, so that they practically overlap one another.

The pump having been filled with water, when the shafts are rotated as described, the water adjacent the hub d will be caught by the blades e and f and thrown outwardly by centrifugal action and also by the blades on the convex sides thereof. As the water leaves the ends of the blades e and f it will be picked up on the convex sides of the blades h , which will, in turn, force the water outwardly, so that it is next picked up on the convex sides of the blades i , and these in turn force it outwardly until it is picked up on the convex sides of the blades k , which force it into the surrounding chamber, from which it will be discharged through the tangential outlet.

As the outer end of each blade extends opposite the inner end of the next, the water is not only effectively prevented from flowing backwardly, but is constantly impelled outwardly and, as the successive sets of blades increase in inclination to the radius from the center outward, the mechanical advantage of the blades on the water is correspondingly increased, so that the force with which the water is impelled as it approaches the casing is rapidly increased. In this connection it may be stated that the action of the inner blades as compared to the action of the outer blades is similar to that of a blunt wedge to a sharp wedge. It will be noted that while the nearer a set of blades is to the periphery, the nearer they approach the tangent, yet the corresponding increase in speed due to their radial position offsets the increase of the angle from the radius, so that the rapidity with which the water is forced outward is not reduced. Inasmuch as the outer blades k lie nearly in the direction of the tangent and move at a correspondingly high velocity, the water may be forced out of the

discharge at the desired pressure without employing a series of pumps.

Having thus described my invention, what I claim as new and desire to secure by Letters Patent is:-

1. A rotary pump comprising a pair of impellers rotatable in opposite directions, one of said impellers having a double series of concentrically arranged blades and the other having a single series of blades concentric with said double series and disposed therebetween, all of said blades being obliquely disposed to a radial position, and the blades of the single series being of opposite obliquity to those of the double series, substantially as described.

2. A rotary pump comprising a pair of impellers rotatable in opposite directions, a double series of blades on each impeller all concentrically and alternately arranged to receive water, one from the other, and all of said blades extending divergently with relation to a radial position, the blades of one series extending oppositely to the blades of the next adjacent series, and the extent of divergency from a radial position being successively increased from the axis outward, so that the outermost blades extend nearly tangentially, substantially as described.

3. A rotary pump comprising a casing, a pair of oppositely rotatable shafts mounted in opposite ends of said casing in axial alignment, one of said shafts having a radially extending support adjacent one end of the casing, said support having an intermediate series of blades mounted thereon at one end and extending towards the opposite end of the casing, a support mounted on the other shaft and extending radially therefrom adjacent and within the first named support and having an inner series of blades mounted at one end thereon within said intermediate series, a support connected to the opposite ends of said inner blades at a distance from the supporting shaft thereof, extending radially adjacent the opposite ends of said intermediate blades from the support thereof and having an outer series of blades mounted thereon extending opposite said intermediate series and the blades of one shaft being oppositely inclined to the blades of the other shaft, substantially as described.

4. A rotary pump comprising a casing, a pair of oppositely rotatable shafts mounted in opposite ends of said casing in axial alignment, one of said shafts having a radially extending support adjacent one end of the casing, said support having a double series of outer blades concentrically mounted thereon at one end and extending towards the opposite end of the casing, a support mounted on the other shaft and extending radially therefrom adjacent and within the first named support and having an inner series of blades mounted at one end thereon, a support con-

ected to the other end of said inner blades, at a distance from the supporting shaft thereof, and extending radially adjacent the opposite ends of said outer blades from the support 5 thereof and having a series of blades mounted thereon at one end and extending between said two series of outer blades, the two series of blades of one shaft being oppositely inclined to those of the other shaft and each 10 outer series being disposed to receive water

from the adjacent inner series, substantially as described.

In testimony whereof, I have signed my name to this specification, in the presence of two subscribing witnesses.
